UNITED STATES PATENT OFFICE.

ROBERT WALTON WIEDERWAX, OF ATLANTIC CITY, NEW JERSEY, ASSIGNOR, BY DIRECT AND MESNE ASSIGNMENTS, TO GEIST MANUFACTURING COMPANY, OF ATLANTIC CITY, NEW JERSEY, A CORPORATION OF DELAWARE.

PREHEATER.

Application filed July 25, 1921. Serial No. 487,534.

To all whom it may concern:

Be it known that I, ROBERT W. WIEDERWAX, a citizen of the United States, residing at Atlantic City, in the county of Atlantic and State of New Jersey, have invented certain new and useful Improvements in Pre-heaters, of which the following is a specification.

This invention relates to preheaters, and 10 is an improvement over the construction shown in my prior Patent, No. 1,338,472, patented April 27, 1920.

In the present invention, I employ an improved type of burner projecting within 15 a casing having a closed bottom and closed sides and provided with a grid forming a top. The casting or other object to be heated, is placed on the grids and covered, and the top of the preheater around the casting 20 is covered whereby air may enter the interior of the preheater casing only through the air inlet openings of the burner. I have found that where the introduction of air is limited to the air openings in the burner, 25 the use of a mass of refractory aggregates, and like materials entirely filling the preheater casing, is unnecessary and the necessary high degree of heat may be obtained through the use of a single layer of aggregates.

In prior constructions of liquid fuel burners wherein a vaporizing retort surrounds the burner, it has been the usual practice to employ a retort formed of a pair of spaced 35 walls extending from a point in the rear of the burner outlet to the front of the combustion chamber. The provision of a vaporizing space extending rearwardly the entire length or substantially the entire 40 length of the combustion chamber is disadvantageous in that the oil passing through the retort is not entirely subjected to a temperature sufficiently high to vaporize it. The temperature at the rear of the 45 combustion chamber, adjacent the air inlet, is considerably lower than the flash-point of the oil with the result that oil passing through this portion of the chamber is only partially vaporized causing carbon deposits within the combustion chamber when the improperly vaporized oil is burned. The provision of a retort that does not properly 50 vaporize the oil also leads to variations in

pressure in the oil system which is further disadvantageous.

In the present invention, I employ a burner surrounded by a casing forming a combustion chamber, the rear of the casing being open to permit introduction of air. The front of the casing is reduced in cross section and the vaporizing retort is formed within the walls of the reduced portion. This reduced portion is so designed that the flame from the burner will strike the walls of the combustion chamber at the rear end of the reduced portion whereby the entire vaporizing retort is subject to a high temperature and the oil properly vaporized. The section of the wall of the combustion chamber beyond the vaporizing retort is maintained cool at all times by the passage of air and the absence of heated oil therein, reducing carbon deposits to a minimum.

In the accompanying drawings, I have shown one embodiment of the invention. In 75 this showing:

Figure 1 is a front elevation of the preheater,

Figure 2 is a vertical sectional view on line 2—2 of Figure 1,

Figure 3 is a detail longitudinal sectional view through one of the burners,

Figure 4 is a vertical transverse sectional view on line 4—4 of Figure 3.

Figure 5 is a central horizontal sectional view thereof,

Figure 6 is a vertical transverse sectional view of a portion of the preheater casing, and,

Figure 7 is a plan view of a portion of 90 the preheater casing, with the grid removed.

Referring to the drawings, the reference numeral 1 designates the side walls of the preheater casing, supported on suitable legs or supports 2. As shown, the walls are 95 formed of metal or other suitable material, and provided with upper and lower flanges 3 for the reception of suitable heat insulating bricks or blocks 4. The casing is provided with a closed bottom 5, and a plurality of transverse bars or strips 6 are arranged over the casing forming a grid.

One of the walls of the casing is provided with suitable openings for the reception of the burners. Any suitable number 105 of burners may be employed, each of the

burners comprising an outer casing 7 forming the combustion chamber. The forward end of the casing is reduced in height, as at 8, and formed relatively broad, as at 9. 5 Within this forward portion of the casing, there is provided a retort space 10, communicating with a main oil feed pipe 11, by means of a branch pipe 12. The retort is provided with an outlet pipe 13, communicating with 10 a valve casing 14, arranged at the rear of the combustion chamber. As shown, the valve casing is provided with a nozzle 15, having a needle valve 16 arranged therein, and controlled by a suitable valve handle 17. The 15 line of the flame projecting from the burner is indicated in Figure 3 of the drawings by dotted lines 18.

The bottom of the casing is supported on transverse members 19. At suitable intervals, between each pair of burners, a pair 20 of angle irons 20 are arranged, one section of the angle iron serving as a support for the bottom of the casing, and the other supporting a vertical partition wall 21 formed 25 of fire brick or other suitable material. A single layer of refractory aggregate 22 is arranged on the bottom of the casing. The aggregates are arranged to provide a substantially V-shaped space 23 adjacent each 30 burner which is substantially free of aggregates. As shown, a few aggregates 24 may be scattered in this space.

In operation, the fuel to be burned is delivered to the retort 10 through pipes 11 and 35 12. The provision of a retort arranged entirely at the front of the combustion chamber forwardly of the point where the flame strikes the walls of the combustion chamber, insures a temperature within the retort 40 sufficiently high to properly vaporize the oil. This provides a fuel which will burn properly without deposition of carbon. The elimination of a vaporizing chamber extending rearwardly into the cooler part of 45 the combustion chamber also reduces the deposition of carbon, in that the walls 7 of the combustion chamber rearwardly of the vaporizing space are maintained substantially cool. The provision of a vaporizing chamber having a relatively uniform 50 temperature further eliminates variations in pressure due to improper vaporization when the retort extends rearwardly into the cooler portion of the combustion chamber.

55 By employing a preheater having its side walls and bottom entirely closed, a casting to be heated or other object is placed on the grids 6 forming the top, and covered. If the casting is not sufficiently large to cover 60 the entire preheater, the grids surrounding the casting may also be covered with plates

of metal, or other suitable material. This eliminates introduction of air into the preheater casing except through the openings 65 at the rear of the burners, and produces a high temperature flame which may be directed entirely across the preheater casing, thus avoiding the necessity of employing a mass of mineral aggregates, or similar materials, entirely filling the casing to 70 equalize the heat within the preheater casing.

The flame from the burner spreads substantially in a cone and strikes the aggregates arranged at the edge of the V-shaped 75 space 23 at an angle. The aggregates being disposed below the plane of the burner, that portion of the flame which passes downwardly, is deflected toward the top of the casing and an equal distribution of heat 80 is obtained.

Referring to Figure 2 of the drawings, it will be noted that the burner casing projects inwardly into the preheater casing to a point beyond the rear of the retort space 85 10. Thus the outer wall of the retort will be heated to the temperature existing within the preheater casing and further assist in the proper vaporization of the fuel.

It is to be understood that the form of 90 my invention herewith shown and described is to be taken as a preferred example of the same, and that various changes in the shape, size, and arrangement of parts may be resorted to without departing from the 95 spirit of the invention or the scope of the subjoined claims.

Having thus described my invention, I claim:

1. A preheater having a closed bottom, 100 closed sides, and an open top, burners projecting through one of the walls thereof, a layer of refractory aggregates arranged within said preheater, and means for supporting an article to be heated on the top 105 of said preheater.

2. A preheater having a closed bottom, closed sides, and an open top, burners projecting through one of the walls thereof, a 110 layer of refractory aggregates arranged therein, said aggregates being arranged to provide a substantially V-shaped space adjacent each burner which is substantially free of aggregates, and means for supporting an article to be heated on the top of 115 said preheater.

In testimony whereof I affix my signature in presence of two witnesses.

ROBERT WALTON WIEDERWAX.
